UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed November 24, 1924. Serial No. 751,731.

This invention relates to improvements in brakes.

An object of the invention is to provide a brake mechanism arranged to be operated from the inside or outside of a railway car, wherein the construction of the brake is greatly simplified in a manner facilitating rapid assemblage and increased efficiency in operation.

10 A further object of the invention is to provide mounting means in the form of oppositely disposed housings which are arranged to freely removably contain the brake operating mechanism when detached, the 15 construction being such that when the housings are secured to the car wall all the operative parts of the brake mechanism are held in assembled relation by such housings.

A still further object of the invention is 20 to provide removable bearing members which extend through the wall of the car, one of such bearing members having a plurality of bearing points, such bearings being arranged to be held in operative relation by 25 securing the housings with which the bearings are associated to the car wall.

Still another object of the invention is to provide a novel ratchet operating mechanism for use in connection with a brake of 30 this character, said mechanism including an actuating member having means adapted to coact with the ratchet wheel and fulcrum means cooperating with an abutment on the housing of the brake, whereby upon swinging movement of such actuating member, the ratchet coacting means travels from its normal inoperative position into operative engagement with the ratchet, the fulcrum means moves out of contact with the abut- 40 ment on said housing, and continued swinging movement of the actuating member serves to rotate the ratchet wheel and the brake drum connected therewith, the construction being such that the actuating member 45 when released returns to normal inoperative position under the influence of gravity.

Other objects and advantages of the invention will more clearly appear from the description and claims hereinafter following.

50 In the drawings, Figure 1 is a front elevation of the invention, showing the interior construction thereof in dotted lines. Figure 2 is a sectional view of the invention on the line 2-2 of Figure 1, some portions of mechanism being shown in elevation. Fig-

ure 3 is a rear elevation of the invention, the interior construction thereof being shown in dotted lines, and Figure 4 is a sectional view of the device similar to Figure 2, showing a slightly different embodiment of the 50 invention.

Referring more particularly to Figure 2 of the drawings, 10 represents a wall of a railway car of well-known construction, to which the brake is adapted to be secured, 65 such wall being provided with openings 11 in the usual manner for mounting a brake of the character contemplated herein. The brake preferably includes oppositely disposed housings A and B, the housing A being 70 adapted for disposition on the outer side of the wall 10 and the housing B on the opposite side of such wall, as shown. The housing A is preferably provided with securing lugs 12, having openings therein for the insertion of 75 retaining bolts 13, such retaining bolts in the secured position of the parts extending through the wall 10, and engaging lugs 14 formed on the housing B.

The housing A is preferably provided with 80 a curved side wall 15, and end wall 16, the walls 15 and 16 cooperating to provide an interior chamber preferably sub-divided by means of a partition 17 to form a relatively 85 large compartment 18, and a smaller compartment 19, the partition 17 having an opening 20 therein, and being provided along its outer edge with a strengthening rib 21. The housing A is also provided with a slot 22, communicating with the chamber 90 19, for a purpose which will presently appear. The end wall 16 of the housing A is provided with an inwardly disposed boss 23, having an opening 24 therein, such opening 95 preferably being surrounded by an annular rib 25, the outer edges of the end wall 16 having strengthening ribs 26 thereon. The housing B is similar to the housing A, having an interior chamber 27, provided by the side wall 28, and the end wall 29, the side 100 wall 28 having a slot 30 therein, and the end wall 29 having an opening 31 therein.

Disposed in housing A is a bearing member 32, preferably including a flange 33 adapted to abut against the outside of the 105 wall 10 of the car, such bearing member having a hollow hub portion 34, extending through the openings 11 formed in the wall 10, such hub portion being provided with spaced bearing surfaces 35 and 36. The 110

flange 33 of the bearing member 32 is arranged to rest in a seat 37 formed in an offset portion of the housing A as shown, and in this position serves as a means for closing the housing A, and to retain various parts of the mechanism therein when the housing is secured to the supporting wall 10.

Disposed in the housing B is a cooperating supporting member 38 provided with a flange 39 arranged to rest against the inside of the wall 10, and a bearing hub 40 having an opening adapted to accommodate the adjacent inner end of the hub portion 34 as shown. The member 38 is held in position in the same manner as the bearing member 32, that is, by means of a seat 41 formed by offsetting a portion of the inner edges of the side walls of the housing B, and such member serves as a retaining means for mechanism disposed in the housing B when the housing is secured in position.

Disposed in the housings A and B is a cylindrical operating shaft 42, such shaft extending through the hub portion 34 and having bearing engagement with the bearing surfaces 35 and 36 of such hub portion, a reduced squared portion 43 of such shaft extending into the chamber 27 of the housing B and having its extremity disposed in the opening 31 in the end wall 29 of such housing. The shaft 42 also extends through the compartments 18 and 19 of the housing A, the outer end of such shaft being cylindrical and freely mounted within the opening 24 in the end wall 16, and having a flange 44 thereon adapted to abut against the boss 23 to limit the endwise movement of the shaft. The portion of the shaft 42 disposed in the chamber 18 is arranged to provide a winding drum 45, such drum having secured thereto by any suitable means, the chain 46, which is connected with the brake shoes in the usual manner. The shaft 42 also has a ratchet wheel 47 preferably formed integral therewith, such ratchet wheel being located in the chamber 19 of the housing A, the ratchet wheel preferably having a hub 48 formed thereon which is arranged to abut against the flanged portion 33 of the bearing member 32 to limit the endwise movement of the shaft 42 in the same manner as the flange 44 but in the opposite direction and it should be noted that by reason of the reduced friction surfaces afforded by the flange 44 and the hub 48, all tendency of the parts to bind is eliminated.

An actuating member in the form of a lever 49 is provided for operating the ratchet wheel 47, such lever having a laterally extending operating portion 50, such portion being curved to correspond with the inner walls of the housing A, as clearly shown in Figure 1 of the drawings. The operating portion 50 has a tooth 51, adapted to cooperate with the ratchet wheel 47, and a fulcrum

part 52 which cooperates with the fulcrum abutment 52^a on the housing A. The operating portion 50 is preferably integrally formed with a connecting member 53, which has an elongated opening 54 adapted to loosely receive the hub 48 of the ratchet wheel. By this arrangement upon movement of the lever 49 in the direction indicated by the arrow shown in Figure 1, the portion 52 fulcrums on the abutment 52^a provided by the housing so as to cause the tooth 51 to move into engagement with the ratchet wheel 47, the opening 54 permitting this fulcruming movement of the operating portion 50 with reference to the housing A. Eventually this action causes the tooth 51 to become fully seated against one of the teeth of the ratchet wheel 47, at which time the upper left-hand edge of the wall surrounding the opening 54 (as seen in Fig. 1), engages the hub portion 48 of the operating shaft. Thereupon, the operating handle being thus locked to the shaft 42, further movement of the lever 49 in the direction of the arrow causes the fulcrum part 52 of the lever to move out of contact with the abutment portion 52^a of the housing, bringing about rotation of the shaft and imparting winding movement to the drum 45, the swinging movement of the lever being limited by the end of the slot 22 within which it moves. Upon release of such lever, the same falls into its normal position through the influence of gravity, thereby disengaging the tooth 51 from the ratchet wheel 47 by reason of the lever 49 fulcruming on the abutment 52^a in a direction the reverse of that heretofore described. A spring operated pawl 55 is provided for preventing retrograde movement of the ratchet wheel 47, such pawl being releasable by means of the lever 56, when desired.

The housing B on the inside of the car is also provided with operating mechanism including ratchet wheel 57, mounted on the reduced squared portion 43 of the shaft 42, such ratchet wheel having a hub 58 formed thereon. A lever 59, similar to the lever 49, is provided, such lever having an operating portion 60, a ratchet engaging tooth 61, and a fulcrum part 62 adapted to engage an abutment portion 62^a on the housing in the same manner as the lever 49, the ratchet operating portion 60 preferably being integrally formed with a connecting member 63, having an elongated opening 64 for receiving the hub 58, the lever 59 operating in the slot 30 in the same manner as above explained. A release lever 56^a similar to the lever 56 is provided in the housing B, and such levers are connected by means of a shaft to move in unison in the usual manner in brakes of this character, such for instance as shown in Patent No. 1,240,324.

An important feature of the invention re-

sides in the cooperative relation of the parts of the brake, such parts being so designed as to permit of rapid assemblage thereof. The parts of the brake are assembled before the housing A is secured in position upon the wall 10 of the car. The release lever 56 and actuating spring are first mounted in operative position within the housing. The shaft 42 is next inserted through the opening 54 of the lever 49, and the latter member is then inserted in an angular direction through the slot 22 of the housing A until the greater portion of the lever proper projects therethrough, the shaft being also meanwhile tipped at an angle relative to the housing. The shaft is then entered from the inner end of the housing through the opening 20 in the partition 17, the shaft and lever then being brought simultaneously to their final normal position relative to the housing, with the end of such shaft extending into the opening 23 of the housing, the drum being thereby arranged in the compartment 18, and the ratchet wheel in the compartment 19, the lever 49 hanging vertically therefrom through the opening 22 with the hub 48 of the shaft extending through the opening 54 thereof. The bearing member 32 is then slipped onto the shaft 42, so as to rest in the seat 37. It is apparent that the housing A with the associated parts can now be secured to the wall 10 by the retaining bolts 13, so that all of the parts of the mechanism are positively held in operating position, so long as the housing is secured to the wall 10. The mechanism thus far described is complete in itself, and could be used separately, the housing in this position providing two points of bearing, 35 and 36 on the single member 32 for the shaft 42, thereby obviating the difficulties heretofore experienced in assembling brakes of this type where the bearings for the shaft are provided in separate members. The housing B is assembled by first placing the inner release lever 56^a in position therein, then inserting the operating lever 59 through the slot 30 into its proper position. The ratchet wheel 57 is then assembled with the hub 58 projecting through the opening 64 of the lever, after which the bearing member 38 is placed in position therein, so as to receive the inner end of the hub 34, the reduced portion of the shaft 42 extending through the ratchet wheel, and the connecting member of the lever 59. After inserting the inner end of the release lever shaft into the opening therefore in the inner release lever, the whole assembly is then shoved back against the car wall and bolted thereto. Thus, when the housing B is secured to the wall 10, the entire operating mechanism of the brake is arranged to be operated from either the outside or inside of the car and it should be noted that the brake assembly contained in the

housing B is capable of considerable longitudinal adjustment relative to the end of the hub 34, in this manner compensating for variations in thicknesses of car walls which occur in practice.

Another important feature in the invention resides in providing the operating handles 49 and 59 which are similar in all respects. It should be observed that the operating portion 50 of the lever 49 eliminates the necessity for a separate connecting link, ordinarily swingably mounted on the operating shaft in brakes of this character, to which the lever is pivotally connected. In operating the lever 49 initial swinging movement of the lever will cause the same to fulcrum on the fulcrum part 52, the opening 54 permitting bodily radial displacement of the lever, causing the tooth 51 to move into engagement with the ratchet wheel and the part 52 to move out of contact with the fulcrum portion 52^a of the housing and the upper left-hand edge of the opening 54 to engage the shaft, continued swinging of the lever serving to rotate the ratchet wheel. The swinging movement of the lever 49 is limited by the end of the slot 22, so that the lever will return to normally inoperative position under the influence of gravity when released, and the slot 30 limits the swinging movement of the lever 59 in a like manner, the operation of such lever being the same as described with respect to the lever 49.

Referring to Figure 4, a slightly different embodiment of the invention is illustrated, such embodiment including the housings A' and B', supporting wall 110, and operating mechanism of the character above explained, including a shaft 142, a ratchet wheel 143, a winding drum 144, an operating lever 145 and the usual connecting link, all disposed in the housing A'.

In this form of invention the housing B' is provided with an integral wall 146, upon which is mounted an integral hub 147, extending into openings formed in the wall 110, there being a bearing member 132 mounted in the housing A', such member having a portion 148 adapted to fit over the end of the hub 147, the inner end of the hub serving as a bearing for the shaft 142. The shaft 142 is preferably provided with a reduced end portion 149 which is square in cross-section, the extremity 150 of the shaft being round in cross-section, and mounted in a bearing opening 151 in the end wall of the housing B'. A ratchet wheel 152 is mounted on the square portion 149 of the shaft 142, such ratchet wheel having a hub 153 adapted to have mounted thereon a connecting link 154 to which the lever 155 is pivotally connected as at 156, this lever being the ordinary type of operating lever shown in connection with brakes of the character described in detail in Patent No. 1,240,324. The mech-

anism included in this embodiment of the invention is assembled in practically the same manner as before described, the differences in this construction residing in providing the integral hub 147 and the bearing member 151, which provides a braced two-point bearing member for the shaft 142 on a single member.

I have herein shown and described what I now consider the preferred manner of carrying out the invention, but the same is merely illustrative, and I contemplate all changes and modifications that come within the scope of the claims appended hereto.

15 What I claim is:

1. In a brake, the combination with a support; brake operating mechanism, including a shaft and a removable bearing member for said shaft provided with a plurality of bearing surfaces; means for mounting said brake operating mechanism, said means being arranged to removably hold said brake operating mechanism when detached from said support, and serving to position said brake operating mechanism and said bearing member in operative assembled relation when secured to said support.

2. In a brake, the combination with a support; of brake mechanism including a shaft, extending through said support; normally removable bearing members for said shaft, one of said members including a hub portion provided with a plurality of spaced bearing surfaces and the other of said bearings having means for slidable reception of said hub portion; and means for securing said bearing members in operative position.

3. In a brake, the combination with a housing; of brake operating mechanism mounted in said housing, said mechanism including a ratchet wheel, and an actuating member provided with means adapted for engagement with said ratchet wheel, said member having means providing a fulcrum for engagement with said housing, whereby operative movement of said lever causes operative engagement of said ratchet engaging means with said ratchet wheel.

4. In a brake, the combination with a housing; of brake operating means in said housing, said brake operating means including a ratchet wheel, and a swingable lever mounted in said housing, said lever having a laterally extended portion, provided with a ratchet engaging tooth adjacent one end, and the other end of said portion providing a fulcrum for engagement with said housing.

5. In a brake, the combination with brake operating mechanism, said mechanism including a shaft; a ratchet wheel mounted on said shaft; a swingable lever for operating said ratchet wheel, said lever being loosely mounted on said shaft; means providing an abutment adjacent to said ratchet wheel;

and means associated with said lever including a portion adapted to engage said ratchet wheel, and a portion cooperating with said abutment to effect contact of said ratchet engaging portion with said ratchet wheel. 70

6. In a brake, the combination with a support; of brake operating mechanism, including a ratchet mechanism; means for mounting said brake mechanism, said means being arranged to normally removably contain 75 said brake mechanism, and serving to hold the same in operative relation when secured to said support; of means providing an abutment adjacent to said ratchet mechanism; and an actuating member for operating 80 said ratchet mechanism, said member including a portion adapted to engage said ratchet mechanism, and a portion cooperating with said abutment to effect engagement 85 of said portion during the operative movement of said member.

7. In a brake, the combination with a support; of brake operating mechanism including a shaft, and ratchet mechanism; means for mounting said brake mechanism, said means being arranged to normally removably contain 90 said brake mechanism, and serving to hold the same in operative relation when secured to said support; a lever for operating said ratchet mechanism, said lever being loosely mounted on said shaft; means providing an abutment adjacent to said ratchet wheel; and means associated with said lever including a portion adapted 95 to engage said ratchet wheel, and a portion cooperating with said abutment to connect said engaging portion of said lever with said ratchet during the movement thereof.

8. In a brake, the combination with a supporting wall; a bearing member extending 105 through said wall, and being provided with spaced bearing surfaces; a shaft extending through said bearing member and rotatably supported by said spaced bearing surfaces, said shaft having a winding drum integral 110 therewith; ratchet mechanism upon the inner and outer sides of said support and supported from said shaft; and means for securing said bearing member in operative position.

9. In a brake, the combination with a supporting wall; a bearing member extending through said wall, and being provided with spaced bearing surfaces; a shaft extending through said bearing member and rotatably supported by said spaced bearing surfaces, said shaft having a winding drum integral 120 therewith; ratchet mechanism upon the inner and outer sides of said support and supported from said shaft; means for securing said bearing member in operative position, said securing means being in the form of housings arranged over the ends of said shaft which project at either side of said support. 125

10. In a brake mechanism, the combination with a support, of a bearing member extending through said support and provided with a plurality of spaced bearing surfaces; 5 a shaft extending through said bearing member and rotatably supported by the bearing surfaces thereof, said shaft being provided with a winding drum and a ratchet wheel at one side of said support, and having means adapted for the reception of a ratchet at the opposite side of said support; 10 an operating lever supported from said shaft and adapted to coact with the ratchet wheel thereon; a ratchet wheel and operating lever arranged at the opposite side of said support on the portion of said shaft provided therefor; and means for supporting said bearing member in operative position. 15
- 20 11. In a brake mechanism, the combination with a support, of a bearing member extending through said support and provided with a plurality of spaced bearing surfaces; a shaft extending through said bearing

member and rotatably supported by the bearing surfaces thereof, said shaft being provided with a winding drum and a ratchet wheel at one side of said support, and having means adapted for the reception of a ratchet at the opposite side of said support; 30 an operating lever supported from said shaft and adapted to coact with the ratchet wheel thereon; a ratchet wheel and operating lever arranged at the opposite side of said support on the portion of said shaft provided therefor; means for supporting said bearing member in operative position, 35 said means including an element adapted to engage the free end of said bearing member to support the same; and housings arranged to enclose the mechanism associated with the projecting ends of said shaft on opposite sides of said support. 40

In witness that I claim the foregoing I have hereunto subscribed my name this 21st 45 day of November, 1924.

STACY B. HASELTINE.
